W. H. NEEDHAM AND N. J. VILE,
LEVER FOR LOOM DOBBIES,
APPLICATION FILED JUNE 12, 1920.

1,369,700.

Patented Feb. 22, 1921.

UNITED STATES PATENT OFFICE.

WILLIAM H. NEEDHAM AND NORMAN J. VILE, OF WORCESTER, MASSACHUSETTS,
ASSIGNORS TO CROMPTON & KNOWLES LOOM WORKS, A CORPORATION OF
MASSACHUSETTS.

LEVER FOR LOOM-DOBBIES.

1,369,700.

Specification of Letters Patent.

Patented Feb. 22, 1921.

Application filed June 12, 1920. Serial No. 388,600.

To all whom it may concern:

Be it known that we, WILLIAM H. NEEDHAM and NORMAN J. VILE, citizens of the United States, both residing at Worcester, in the county of Worcester and State of Massachusetts, have invented a new and useful Lever for Loom-Dobbies, of which the following is a specification.

This invention relates to a lever designed for use in a loom dobbby.

Such levers, commonly known as hook levers, are used in considerable numbers in loom dobbies and are necessarily very closely limited as to thickness.

It is one object of our invention to improve the construction and lower the cost of manufacture of such levers by constructing the same from a single piece of sheet metal.

Another feature of our invention relates to the vision of a novel connection by which the dobbby hooks may be easily secured to the lever.

Further features of our invention relate to arrangements and combinations of parts hereinafter described and more particularly pointed out in the appended claims.

A preferred form of our invention is shown in the drawings in which—

Figure 1 is a sectional elevation of certain parts of a loom dobbby, showing our improved lever in its operation position;

Fig. 2 is a side elevation of the lever and the attached hooks;

Fig. 3 is an edge elevation of the lever;

Fig. 4 is a sectional plan view of one end of the lever, taken along the line 4—4 in Fig. 2;

Fig. 5 is a side elevation of one end of the lever when partially completed;

Fig. 6 is a collective view of one end of the lever, one end of a hook, and the bushing which is used to connect the hook to the lever, and

Fig. 7 is an enlarged side elevation of the bushing.

Referring to the drawings, Fig. 1 shows certain parts of a well known loom dobbby and illustrates the conditions under which our improved levers are used. The parts shown comprise the dobbby frame 10, a jack or harness lever 11 pivoted to the frame at the point 12, a lifter bar 13, an indicator rod 14, upper and lower combs 15 and 16, upper and lower hooks 17 and 18, and a hook lever 19 pivoted at 20 to the jack 11.

The construction of the lever 19 is clearly shown in Figs. 2, 4 and 5. Each lever is made from a single piece of sheet metal and is punched or pressed out with lateral projections 21, 22 and 23, indicated in dotted lines in Fig. 2. The projecting portion 21 is bent over against the main portion of the lever to form a bearing of double thickness for the pivot 20, as indicated in Fig. 3. The end projections 22 and 23 are bent around as indicated in Fig. 4 to form spaced bearing portions for the bushings 24 by which the hooks 17 and 18 are secured to the lever 19. It will be noted that the portions 22 and 23 are bent along the same longitudinal edge of the lever 19 but that they are disposed on opposite sides of the lever for convenience in assembling the dobbby.

Openings 25 extend through the separated end portions of the lever and one of the openings at each end is also provided with a notch 26. The hooks 17 and 18 are similarly provided with openings 27 also having notches 28. Each bushing 24 is formed to fit the openings 25 and 27 and is provided with a lug or projection 29 fitting the notches 26 and 28.

In assembling the parts, the hooks are placed in the dotted line positions shown in Fig. 2, with the notches 28 in the hooks alined with the notches 26 in the levers. The bushings are then inserted and the lugs 29 are pushed through the notches 26 and are positioned in the notches 28. The hooks are then swung around to the full line or operative position shown in Fig. 2, in which positions the notches 26 and 28 are out of alinement and the lugs 29 prevent axial displacement of the bushings. The parts are thus very easily assembled without the use of any tools and may be as easily separated should occasion arise.

As the levers 19 rock against cross bars 30 and 31, (Fig. 1) when one of the hooks 17 or 18 is pulled to the right, it is desirable to round off the extreme ends of the levers as indicated at 32 in Fig. 2.

Having thus described our invention, it will be seen that a strong and durable lever is provided that may be cheaply and easily constructed, and that an extremely simple and convenient connection is also provided for securing the hooks thereto.

Having thus described our invention, it will be evident that changes and modifications can be made therein by those skilled

in the art within the spirit and scope of our invention as set forth in the claims and we do not wish to be otherwise limited to the details herein disclosed, but what we claim
5 is:—

1. A lever for a loom dobby comprising a single piece of sheet metal having spaced bearing portions at both ends of said lever, the two parts of each bearing portion being joined along one edge only and having a U-shaped transverse cross-section, and said connecting edges being disposed longitudinally of said lever.

2. A lever for a loom dobby comprising a single piece of sheet metal bent to form a center bearing of double thickness, and end bearings each having an off-set portion, said off-set portions being disposed on opposite sides of said lever and being joined to the body of the lever along a single edge extending longitudinally of said lever and at the same edge thereof.

3. In a dobby, a lever having spaced bearing portions with aligned openings therein, one of said openings having a notch, a dobby 25 hook having a corresponding notched opening, and a bushing for said hook fitting said several openings and having a lug adapted to pass through the notch in said lever and to be received in the notch in said hook, 30 said notches being out of alignment when the hook and lever are disposed in operative relation.

4. A lever for a loom dobby comprising a single piece of sheet metal having spaced bearing portions at both ends of said lever, the two parts of each bearing portion being joined along one outer edge only.

In testimony whereof we have hereunto affixed our signatures.

WILLIAM H. NEEDHAM.
NORMAN J. VILE.
